UNITED STATES PATENT OFFICE.

VIRGIL DRAPER, OF NORTH ATTLEBOROUGH, ASSIGNOR TO OSCAR M.
DRAPER, OF BRISTOL, MASSACHUSETTS.

DESIGN FOR AN ORNAMENTAL CHAIN-LINK.

Specification forming part of Design No. **6,782**, dated July 22, 1873; application filed May 24, 1873.

B.

To all whom it may concern:

Be it known that I, VIRGIL DRAPER, of North Attleborough, in the county of Bristol and State of Massachusetts, have invented a new and Improved Design for Ornamental Chain-Links; and I do hereby declare that the following specification, taken in connection with the drawing making a part of the same, is a full, clear, and exact description thereof.

The design for an ornamental chain-link, exhibited in the drawing, is formed by two links proper, *a b*. Midway between the ends of these two links is placed a central member, *c*, whose axis is set at right angles with the

longitudinal axes of the links *a b*. The space around the bar *c*, between the two links *a b*, is filled with fillet *d*.

What I claim as new, and desire to secure by Letters Patent, is—

1. The design for an ornamental chain-link, herein described and shown.
2. The design for an ornamental chain, herein described and shown in Figure 3 of the drawing.

VIRGIL DRAPER.
